DESIGN FOR A COMBINATION FOOTSTOOL AND MAGAZINE RACK

Albert Joseph Warth, Sr., Canton, Ohio

Application February 4, 1942, Serial No. 105,643

Term of patent 3½ years

To all whom it may concern:

Be it known that I, Albert Joseph Warth, Sr., a citizen of the United States, residing at Canton, in the county of Stark and State of Ohio, have invented a new, original, and ornamental Design for a Combination Footstool and Magazine Rack, of which the following is a specification, reference being had to the accompanying drawing, forming part thereof.

Figure 1 is a perspective view of a combination footstool and magazine rack, showing my new design.

Figure 2 is a rear elevational view; and Figure 3 is an end elevational view thereof.

I claim:

The ornamental design for a combination footstool and magazine rack, as shown.

ALBERT JOSEPH WARTH, SR.
